United States Patent Office.

W. H. LAUBACH, OF PHILADELPHIA, PENNSYLVANIA, ASSIGNOR TO HIMSELF AND W. S. COOPER, OF SAME PLACE.

Letters Patent No. 63,061, dated March 19, 1867.

IMPROVEMENT IN LOW-WATER INDICATORS.

The Schedule referred to in these Letters Patent and making part of the same.

TO ALL WHOM IT MAY CONCERN:

Be it known that I, W. H. LAUBACH, of Philadelphia, Pennsylvania, have invented an Improved Low-Water Alarm for Steam Boilers; and I do hereby declare the following to be a full, clear, and exact description of the same, reference being had to the accompanying drawing, and to the letters of reference marked thereon.

My invention consists of an instrument fully described hereafter, to be attached to a steam boiler for the purpose of giving an alarm when the water becomes unsafely low; also of a device for maintaining the interior of a glass tube which serves as a water gauge, and which is attached to the instrument, free from deposit.

In order to enable others to make and use my invention, I will now proceed to describe its construction and operation. On reference to the accompanying drawing, which forms a part of this specification—

Figures 1 and 2 are sectional elevations of my improved low-water alarm showing the parts in different positions.

Figure 3 is a side view; and

Figure 4, a front elevation partly in section.

To the front plate X of a steam boiler are secured two pipes, A and A', which communicate with the interior of the boiler, one at a point above and the other at a point below the proper water level, and in each pipe is a socket for the reception of one end of a glass tube, B. From the pipe A projects a branch, a, which communicates with a steam-tight case, C, and through the front of the latter extends a spindle, b, to which are secured the arm e, inside the case, and the arm e', on the outside of the same. Within the case C are two levers D E, knife-edge bearings e e, on each lever, resting on bearings on a frame, F, secured within the case, and at the outer end of the lever D is a hook, i, which, when the levers are in the position shown in fig. 1, fits into a hooked projection, n, on the lever E. To the outer end of the lever E is hung a weight, d, and from the inner end is suspended (by a wire, f,) a weight or float, g, the latter occupying such a position within the tube B that it will be immersed in water when that in the boiler is not below its proper level. To the outer end of the arm e' is hung an adjustable weight, h, and to the end of the arm e is hung a pawl, k, a shoulder, x, at the lower end of which (when the parts are in the position shown in fig. 1) bears on the end of the lever D. To a branch, a', projecting from the pipe A, is secured an ordinary steam whistle, H, the valve s of which is so connected to a spindle, m, as to be opened when the latter is depressed, the spindle projecting above the top of the whistle, and its end being below the arm e'. The valve s is maintained in contact with its seat by a spring, o, which is coiled round the rod m, and which intervenes between the top of the whistle, and a pin on the rod. While the float g is immersed in water it is partially supported by the latter, and therefore does not act with its full weight on the lever E, and the weight d consequently maintains the lever in the position shown in fig. 1. When, however, the water in the boiler, and consequently that in the tube B, descends below the proper water line x x, it no longer aids in supporting the float g, the increased weight of which is exerted on the lever E so as to more than counterbalance the weight d; the lever is consequently moved to the position shown in fig. 2. So long as the lever D is secured by the hook n in its horizontal position, it affords a rest for the pawl k, and the latter, with the arms e and e', is maintained in the positions shown in figs. 1 and 4. When, however, on the descent of the water in the tube B, the lever E is so moved as to release the outer end of the lever D, the inner end of the latter will be depressed, and the pawl k and arms e and e' will fall, the arm e' bearing on the spindle m and depressing the valve s, so that the steam is admitted to the whistle and sounds an alarm which indicates to the attendant the unsafe condition of the water in the boiler. The arm e' cannot again be adjusted to its first position until the lever D is secured by the hook n, which is effected when, on replenishing the boiler, the lever E resumes its horizontal position. The arm e' may then be raised until the pawl k rests upon and is supported by the lever D. It will be observed that the float g is somewhat less in diameter than the interior of the tube B, and that there are on the float projecting pins y y, which are nearly in contact with the tube. A deposit is apt to collect in the glass tube, and this deposit would interfere with the free movement of the float but for these projections, which, as the float moves up and down, dislodge the sediment.

I claim as my invention, and desire to secure by Letters Patent—

1. The weighted lever E, controlled by a float or weight g, and having a projection adapted to a catch or

hook on the end of the lever D, in combination with the pawl *k*, arms *a*, weighted arm *a'*, and whistle H, the whole being arranged and operating substantially as and for the purpose herein set forth.

2. The weight or float *g*, and its projections *y*, arranged to operate in the interior of the glass tube B as and for the purpose herein described.

In testimony whereof I have signed my name to this specification in the presence of two subscribing witnesses.

W. H. LAUBACH.
